(57) **CLAIM**

The ornamental design for a bottle, as shown and described.

DESCRIPTION

FIG. 1 is a perspective view of a bottle embodying our design;

FIG. 2 is a front elevation view thereof, the rear elevation view being a mirror image;

FIG. 3 is a right side elevation view thereof;

FIG. 4 is a left side elevation view thereof;

FIG. 5 is a bottom plan view thereof; and,

FIG. 6 is a top plan view thereof.

The broken lines illustrate portions of the bottle that form no part of the claimed design. The dash-dot line in FIG. 5 defines a boundary of the claimed design and forms no part thereof.
